(57) **CLAIM**

The new ornamental design of a miniature fluorescent light bulb, as shown and described.

DESCRIPTION

FIG. 1 is a side elevational view of a miniature fluorescent light bulb, showing my new design.

FIG. 2 is a top plan view of the light bulb shown in FIG. 1;

FIG. 3 is a bottom plan view of the light bulb;

FIGS. 4-7 are side elevational views showing the light bulb from various angles; and,

FIG. 8 is a perspective view of the light bulb.
